UNITED STATES PATENT OFFICE.

DANIEL MCFARLAN MOORE, OF EAST ORANGE, NEW JERSEY, ASSIGNOR TO GENERAL ELECTRIC COMPANY, A CORPORATION OF NEW YORK.

METHOD AND APPARATUS FOR MAINTAINING GASEOUS CONDUCTION DISCHARGES.

Application filed July 22, 1922. Serial No. 576,768.

My invention relates to gaseous conduction devices in which an electric discharge occurs in the space between electrodes mounted in a closed vessel which contains 5 more or less rarefied vapors or gases and more particularly to devices of this character intended to be used as a source of light and so constructed that the vapors or gases are rendered luminous by the electric discharge.

In a typical vacuum tube or gaseous conduction device of the character to which my invention relates the discharge produced by the passage of an electric current thru a 15 tube provided with similar electrodes at each end does not extend uniformly throughout the space between the electrodes. At each alternation of the impressed voltages, there is adjoining the cathode a non-luminous region known as the Crookes dark space. Beyond this is a luminous region known as 20 the negative glow followed by the second or Faraday dark space and beyond this and extending to the anode is a luminous region known as the positive column. In order to obtain a practical intensity of light at good 25 efficiency from an electric discharge in a device of this character the pressure of the gas and the spacing of the electrodes should be so chosen that most of the luminosity is produced by the positive column. Heretofore, in order to obtain such a discharge it has been customary to impress upon the electrodes of such a tube a high potential obtained from the ordinary low potential 30 distribution circuits by means of a transformer, which increases the cost and greatly complicates the lamps.

One object of my invention is to provide 35 a gaseous conduction lamp which will start and operate when connected directly to a lighting circuit of low operating potential, such as 220 volts or even 110 volts, without the use of any auxiliary or external means 40 for raising above the normal operating potential of the line the potential impressed upon the electrodes and which utilizes the efficient positive glow or discharge as the source of light. Another object is to provide 45 a gaseous conduction lamp resembling the incandescent lamp now in common use and provided with a positive column discharge which is in effect a gaseous filament, yet so constructed that the lamp will operate 50 on the ordinary distribution circuit used

for supplying incandescent electric lamps. A further object is to provide a simple and rugged form of gaseous conduction lamp, which has an efficient positive column and yet will operate at potentials far below 60 those which it has been hitherto customary to use to maintain a positive column discharge. A still further object is to improve gaseous conduction lamps in general and the method of operating them as more 65 fully pointed out hereinafter.

In accordance with my invention the gaseous conduction device is constructed with two main electrodes mounted in a closed vessel containing a gas of high conductivity as for example some of the rare gases such as neon or neon mixed with some helium, the pressure of the gas and the spacing of the electrodes being so chosen that the discharge between the main electrodes 70 will consist almost entirely of the positive column. The starting and maintaining of the positive column discharge is so facilitated by my invention that ordinary low voltages, such as used for commercial lighting by incandescent lamps, are sufficient to start and maintain a positive column discharge between the main electrodes. I attain this result by so constructing the device that normal operating potential such 75 as 220 volts or 110 volts when applied to the device will affect the gas adjacent the main electrode in such a manner as to cause the positive column discharge to appear at that potential. To produce the desired effect on the gas I use some means which in response to the normal operating potential of the device will ionize the gas or produce the effect of ionization, whereupon normal potential 80 will maintain the positive column discharge 85 between the main electrodes. The effect is preferably produced by some auxiliary means such as a third electrode mounted adjacent one of the two main electrodes to form one electrode of an auxiliary gap connected in parallel with main electrodes and so constructed that the normal potential of the circuit will cause the desired effect upon the gas in the immediate vicinity of the third electrode and thereby upon the gas between the main electrodes also, whereby a positive column discharge is caused to occur and be maintained at the normal potential 90 of the circuit.

In accordance with my invention the elec- 110

trodes of the auxiliary or ionizing gap are so spaced that at the normal potential of the supply circuit and at the pressure of the gas existing in the vessel, there is so great a resistance offered to a luminous discharge between the electrodes of the auxiliary or ionizing gap that very little or no visible discharge occurs in that gap, while a brilliant positive column discharge occurs and persists between the main electrodes. Apparently this resistance at the electrodes of the auxiliary gap is caused by the Crookes dark space from each electrode extending practically to the other electrode at the potential of the supply circuit. I prefer to confine the discharge from the third electrode to the end of that electrode and one convenient way to do this is to use cylindrical ionizing electrodes and place them in a glass tube having a bore only slightly larger than the ionizing electrodes. Where it is desired that the lamp shall start and operate on a very low potential such as 110 volts, I prefer that one or both of the electrodes of the auxiliary gap be made of or coated or treated with a material having a high electron emissivity, as for example, magnesium, caesium, or some equivalent metal.

This and other aspects of my invention will be more fully explained in the specification following and the novel features of my invention are pointed out with greater particularity in the appended claims, but the invention itself may best be understood in connection with the accompanying drawing in which merely for purposes of illustration I have shown some of the various forms in which my invention may be embodied and in which Figure 1 is a view of one form of lamp embodying my invention; Figure 2 is another form; and Figure 3 is still another form in which the light giving column is curved.

I have shown my invention embodied in lamps which are substantially the size and shape of the incandescent lamps in general use, as this form of embodiment of my invention is very convenient. My invention is not restricted to such lamps, but is equally valuable in any form of gaseous conduction lamp utilizing the positive column as a source of light.

In Figure 1, I have illustrated a form of lamp comprising a bulb 1 quite similar in size and shape to an incandescent lamp and provided with a screw base 2 such as commonly used on incandescent lamps. Leading-in wires 3 for supplying current to the lamp are connected at their outer ends to the contacts of the base as is customary in incandescent lamps, and at their lower ends to main electrodes between which occurs the positive column discharge from which the light is obtained. The lead wires 3 are preferably though not necessarily coated with

glass or other insulation 4 to hinder discharges from them. The main electrodes 5 are preferably made of some metal or material such as magnesium or its equivalent, which has a high electron emissivity. I have found it advantageous to confine the positive column discharge to a definite channel, as for example by a glass or quartz tube 6 open at one or both ends, in which the electrodes 5 are placed so that the discharge is confined to the tube. The length of this tube should be greater than its diameter, and it should be as long as possible to obtain the best efficiency.

I prefer to use in the bulb 1 a rare gas or vapor of good conductivity such as neon, or neon having mixed with it some other rare gas, such as helium. The gas in the bulb is at such a pressure that any discharge initiated and maintained between the main electrodes 5 at the voltages commonly used for operating incandescent electric lamps will consist almost entirely of the positive glow or column. This pressure may range from 5 mm. to 50 mm. of mercury depending upon the character of the electrodes, their spacing, the composition of the gas, and other factors. If the pressure is too low there is merely a faint glow around the electrodes; if the pressure is too high the discharge contracts into a thin threadlike column; but if the pressure is right the positive column discharge fills the tube 6.

In accordance with my invention the gas between the main electrodes is affected or ionized by some means responsive to the low potential commonly used on supply circuits for incandescent lamps so that the discharge between the main electrodes 5 can be started and maintained at that low potential. I prefer to use some means responsive to this low normal potential which will keep the gas between the electrodes ionized at the low potential of the supply circuit. One suitable means responsive to the normal potential of the circuit for supplying incandescent electric lamps is an ionizing gap so proportioned that at normal potential it permits sufficient current to flow to produce a scarcely noticeable discharge, but offers such resistance that at the same potential a large current flows between the main electrodes as a bright positive column discharge in parallel with the discharge in the auxiliary gap. A suitable ionizing gap may be made between one of the two main electrodes and a third or auxiliary electrode 7 or preferably by using two such auxiliary electrodes spaced apart a distance such that an ionizing discharge will occur between them but very little current will flow. When such a gap is connected in parallel with the main electrodes, 5, as shown in Figure 1, and the normal potential of the circuit is impressed upon both pairs of electrodes, a barely visi-

ble discharge will occur between the auxiliary electrodes 7 which apparently ionizes the gap between the main electrodes 5, whereupon a bright and luminous discharge 5 consisting almost entirely of the positive column will start and persist between the main electrodes. I prefer to confine the positive column discharge between the electrodes 7 to their adjacent ends as much as possible as, for example, by enclosing the cylindrical electrodes 7 in a glass tube 8 having a bore only slightly larger than the electrodes. The auxiliary electrodes may be connected in parallel with the main electrodes 15 in any convenient way as for example, by making them an extension of the main electrodes which are preferably made of magnesium wire wound into a spiral as indicated in Figure 1.

20 I have obtained good results with either alternating or direct potential of about 220 volts with a lamp constructed as shown in Figure 1 with the bulb 1 about three inches in diameter and main electrodes 5 made of 25 seven turns of magnesium wire 38 thousandths of an inch in diameter wound to form a sort of cup having a bore about one quarter of an inch. These main electrodes have a gap about three quarters of an inch in 30 length between them and the open ended glass tube 6 is about one and a half inches long with a bore about five sixteenths of an inch. The electrodes 7 of the ionizing gap may to advantage consist of the ends of the 35 magnesium wire composing the main electrodes, these ends being spaced one-thirty-second of an inch apart in a glass tube 8 about five-eighths of an inch long and having a bore such that it fits the electrodes 7 just loosely enough to be moved along them easily. I 40 have found that if the tube 8 fits the electrodes too tightly the auxiliary gap does not function properly. If the tube 8 fits loosely but the length of the gap between the electrodes 45 7 is too great, a luminous discharge like that in a Geissler tube appears in the gap at a normal potential of 220 volts and the electrodes should be moved towards each other until this luminous discharge just disappears, whereupon the length of the gap 50 will be correct.

The bulb 1 was first well exhausted and then filled to a pressure of about 20 mm. of mercury with a mixture of neon and 55 helium containing about 20% helium. Such a lamp when connected to a 220 volt alternating current lighted up immediately with a bright column of light between the electrodes 5 and consumed about 4.5 60 watts when a limiting resistance of 5000 ohms was used.

In Figure 2 I have shown a form of lamp which, in general, is constructed much like Figure 1, but in which the main electrodes 5 65 are so mounted that the discharge between

them is confined to a tube 10 sealed at both ends and communicating with the interior of the bulb 1 through a vent 11 which equalizes the pressure and enables the bulb to act as a sort of reservoir of gas and to prevent 70 wide fluctuations of pressure of the gas through which the discharge is passing. In this particular form of lamp the ionizing gap, mounted outside of the positive column discharge between the main electrodes, and 75 as shown in Figure 2 at a considerable distance from the main electrodes, is constructed substantially like the ionizing gap of the lamp shown in Figure 1 and may be connected to the leads at any place which is convenient. This lamp is constructed with substantially the same gas pressure and electrode size and spacing as that shown in Figure 1. The size of the vent 11 may vary 80 within wide limits, but if too large it prevents the discharge between the main electrodes 5 being confined to form a column of the most advantageous cross section.

85 In Figure 3 I have illustrated another form of lamp in which the ionizing electrodes 7 are mounted adjacent to or immediately behind the main electrodes 5. In this particular form of lamp the discharge between the main electrodes is restricted or 90 confined to a bent tube 12 provided with a 95 vent 13 to the interior of the bulb 1. The tube 12 should have an interior diameter which will restrict the discharge to the cross section at which it has the greatest efficiency. If the tube is made too small the discharge 100 will not pass, while if the tube is made too large the discharge becomes rather diffuse and decreases in intrinsic brilliancy. In all cases it is advantageous to have the envelope around the main electrodes 5 of greater diameter than the bore of the tube which confines the light giving positive column, 105 whether the main electrodes be small or large.

110 In the form of lamp such as shown in Figure 3 the auxiliary gaps may be placed adjacent to the main electrodes 5 and in the same chamber with them. In Figure 3 I have shown two ionizing gaps one for each main electrode but the lamp will function 115 well when only one of the ionizing gaps is used. The electrodes 7 of each gap are connected to opposite sides of the circuit through wires 14 and 15 in the base of the lamp. If the tube 8 of each auxiliary gap 120 is left open at the ends it should be of such a length that a discharge around the outside of the tube encounters greater resistance than a discharge between the main electrodes 5 of the lamp, but I prefer to seal the remote 125 end of each tube enclosing an electrode 7 so as to enclose the ionizing gap in a kind of cup with its open end adjacent to the main electrodes.

130 In many cases I find it desirable to limit

- the amount of energy expended in the ionizing gap to some nominal amount, such as one half watt, by inserting a controlling resistance 16. When such a resistance is used the 70 length of the ionizing gap for 220 volts may be as much as one sixteenth of an inch, although I prefer one thirty-second of an inch and the glass tube 8 can then be made of larger diameter or eliminated.
- 10 3. A lamp may be constructed as shown in Figure 3 suitable for use on a 220 volt circuit with either alternating or direct current with bulb 1; main electrodes 5, ionizing gaps with electrodes 7 and tubes 8, and with the 75 gas in the bulb 1 of the same composition and pressure as above described in connection with the lamp shown in Figure 1. It is immaterial whether the ends of the bent tube 12 are practically side by side so as to 80 make the tube U shaped or whether they are further apart, so long as the main gap in which the positive column discharge occurs between the main electrodes 5 is about one inch long measured along the axis of the 85 bent tube 12. I have found that such a lamp 90 when connected directly to a 220 volt alternating current circuit will light up immediately and operate continuously with a bright positive column discharge in the 95 tube 12.
- 30 4. A low potential gaseous conduction device comprising a sealed bulb containing a rarefied gas of good conductivity, a tube in said bulb having sealed enlarged chambers 100 at its ends, electrodes mounted in said sealed chambers of a cross-section such that the discharge between them is constricted by said tube, an auxiliary electrode mounted in one of said enlargements to form an electrode of a short gap proportioned to permit a non-luminous discharge at the normal potential of the circuit and thereby cause at that potential a discharge between the main electrodes and a current controlling resistance in series with said auxiliary electrode, the pressure of said gas in said bulb being 105 such as to cause the discharge between said electrodes in said tube to consist principally of the positive column.
- 35 5. A gaseous conduction lamp comprising a sealed bulb having a base secured to one end thereof and containing a rarefied gas, a U shaped transparent tube mounted in said bulb and having enlarged sealed chambers 110 at its ends, the bent portion of said tube between said enlargements having a length several times the bore of the tube and a vent to the interior of said bulb, a main electrode in each of said enlargements having a cross-section greater than the bore of 115 said tube, an auxiliary electrode in each of said enlargements spaced from the main electrode in said enlargement to form a discharge gap of such a length as to permit a non-luminous discharge at the operating potential of the lamp, and current controlling resistance in series with said auxiliary electrodes, the gas in said bulb being of such a pressure that the discharge between the electrodes through said U shaped tube consists 120 principally of the positive column.
- 40 6. A low potential gaseous conduction device comprising a closed vessel containing rarefied gas of good conductivity, a U shaped transpar- 125
- 50 1. A gaseous conduction device comprising a closed vessel containing a rarefied gas of good conductivity, a tube mounted in said vessel and having enlarged sealed chambers 130 at its ends and a vent intermediate its ends and an electrode having a cross-section greater than the bore of said tube in each of said chambers, the length of said tube and the pressure of the gas in said vessel being such that the discharge between said electrodes consists principally of the positive column.
- 55 2. A gaseous conduction device comprising a sealed vessel containing rarefied gas of good conductivity, a U shaped transpar-

of main electrodes spaced apart about three-fourths of an inch in said vessel to cause the discharge between them to consist principally of the positive column, a tube having 5 a diameter less than its length for confining the discharge between said electrodes, and auxiliary electrodes spaced apart about one thirty-second of an inch and connected in parallel with the main electrodes, and an 10 open ended glass tube fitting loosely over said electrodes and of a size to permit a non-luminous discharge to occur between said electrodes and start a positive column discharge between the main electrodes.

15 7. The method of maintaining a positive column gaseous conduction discharge at low potential in a rarefied gas between electrodes separated a distance greater than the striking distance of said potential, which 20 consists of ionizing the gas in the vicinity

of one of said electrodes by an auxiliary discharge in said gas at said low potential in parallel to said positive discharge and thru the Crookes dark space only.

8. The method of maintaining a positive 25 column gaseous conduction discharge at low potential in a rarefied gas between electrodes separated a distance greater than the striking distance of said potential, which consists in ionizing the gas in the vicinity 30 of one of said electrodes by an auxiliary discharge in said gas at said low potential in parallel to said positive column discharge and limiting said auxiliary discharge to restrict it to substantially the Crookes dark 35 space.

In witness whereof I have hereunto set my hand this 18th day of July, 1922.

DANIEL MCFARLAN MOORE.
